SALVADOR HERREJÓN LÓPEZ, OF MEXICO, MEXICO

AUTOMATIC SAFETY DEVICE FOR STEAM BOILERS OR GENERATORS

Application filed July 2, 1927, Serial No. 203,192, and in Mexico February 9, 1927.

This invention relates to an automatic safety device for steam boilers or generators, and has for its object to provide, in a manner as hereinafter set forth, a device of such class 5 for preventing to a minimum the bursting of the boilers or generators, as well as the warping or mis-shaping of the walls of the combustion chambers thereof, whereby costs of maintenance are materially reduced.

10 A further object of the invention is to provide, in a manner as hereinafter set forth, a safety device for steam boilers or generators acting to automatically extinguish a fire in the combustion chamber when the water is 15 clear of the top wall or crown sheet of such chamber and when the temperature of said top wall reaches 350° C., further for automatically indicating or signalling when the said top wall of the combustion chamber 20 reaches a temperature of 350° C., and further for automatically extinguishing the fire in the combustion chamber simultaneously with the automatic indicating or signalling when the top wall or crown sheet of the combustion chamber reaches a temperature of 25 350° C., under such conditions reducing to a minimum the bursting of the boilers or generators, as well as the warping or mis-shaping of the walls of the combustion chambers 30 thereof, and therefore reduce accidents to a minimum and decrease the cost of maintenance.

A further object of the invention is to provide, in a manner as hereinafter set forth, a 35 safety device for use in connection with steam boilers or generators and including fusible plugs seating in openings and fusing at a temperature which is not injurious to the walls of a combustion chamber, and with said 40 plugs and the openings in which they are seated, protected from crustation and under such conditions a satisfactory operation of the device will be had when desired, which otherwise would not be.

45 Further objects of the invention are to provide, in a manner as hereinafter set forth, a safety device for the purpose hereinbefore referred to, which is simple in its construction and arrangement, strong, durable, thoroughly efficient in its use, automatic in its

action, readily installed with respect to a steam boiler or generator, and comparatively inexpensive to set up.

With the foregoing and other objects in view the invention consists of the novel construction, combination and arrangement of parts, as hereinafter more specifically described and illustrated in the accompanying drawings, wherein is shown an embodiment of the invention, but it is to be understood 55 that changes, variations and modifications can be resorted to which fall within the scope 60 of the claims hereunto appended.

In the drawings wherein like reference characters denote corresponding parts 65 throughout the several views:

Figure 1 is a longitudinal sectional view of a steam boiler or generator showing the adaptation therewith of an automatic safety device in accordance with this invention and 70 with the boiler or generator operated from liquid fuel.

Figure 2 is a fragmentary view in vertical section illustrating a cutoff for the fuel for the burner.

Figure 3 is a section on line 3—3 Figure 1.

Figure 4 is a fragmentary view of a steam boiler or generator showing the adaptation therewith of a pressure controlling element 75 for the cutoff and with said element shown 80 in vertical section.

Fig. 5 is a sectional plan of the cutoff, taken on the line 5—5 Figure 1.

Figure 6 is a fragmentary view in sectional plan illustrating the anchoring end of the 85 pressure controlling element for the cutoff.

The adaptation of an automatic safety device, in accordance with this invention, is illustrated by way of example in connection with a steam boiler or generator which burns 90 liquid or gaseous fuels, but it is to be understood, that the safety device can be employed in connection with steam boilers or generators which burn solid fuels. When used for steam boilers or generators burning liquid 95 or gaseous fuel the device connects with the fuel supply line for closing it, as shown, but when employed for steam boilers or generators burning solid fuels the device is operatively arranged with respect to the air en- 100

trances for closing them to shut off completely the air supply for combustion whereby the fire will be extinguished. When the liquid or gaseous fuel supply line is cut off the fire in the combustion chamber will become extinguished.

Referring to the drawings in detail, 1 indicates the combustion chamber of a steam boiler or generator and 2 the top wall or crown sheet of said chamber 1. Projecting from one end of the combustion chamber 1, that is its inner end, are the calefaction tubes 3. A refractory lining is indicated at 4, an air intake for combustion at 5, a supporting plate 6 for the lining 4, a water chamber 7 which extends around the top, sides and ends of the combustion chamber 1, an entrance 8 to the chamber 1, a door frame 9, a door 10 which controls the entrance or opening 8, the outer casing, shell or wall 11 of the boiler or generator and which in connection with the walls of the combustion chamber 1 provides the water space 7. The upper part of the casing or outer wall 11 in connection with a dome, not shown, provides a storage space 12 for the generated steam. A burner 14 extending inwardly from a fuel supply line 15 is arranged with an opening 13. A valved steam supply line is indicated at 15' and which leads from the storage space 12 to the atomizer of the burner 14. The steam supply line 15' is provided with a manually operated cutoff or valve 16. The fuel supply line 15 is provided with a manually operated cutoff 17. A liquid or gaseous fuel reservoir or container 18 opens into the line 15. The foregoing elements are of known construction and are illustrated by way of example to show the adaptation with a steam boiler or generator of a safety device in accordance with this invention and for the purpose referred to.

A safety device in accordance with this invention comprises a pressure-actuated operating mechanism for a closure means for a fuel supply line or for an air supply intake for combustion, a pressure conducting line leading from the storage space 12 to said mechanism, a plurality of pressure controlling elements connected to and normally closed to the pressure conducting line and opening into said storage space 12, and two indicators or signalling elements normally closed to and for conducting pressure, respectively, one to the outside of the boiler, in connection with a whistle to give alarm, and the other to the chamber 1. The indicating or signalling element is open to the storage space 12. As illustrated, by way of example, the pressure-actuated operating mechanism is connected to a rotatable closure valve 18' of the tapered plug type provided with a one-way port 19. The valve 18' is shiftably mounted in a casing 20 interposed in the fuel supply line 15, below the manually operated cutoff 17. The valve 18' includes at its larger end a stem 21,

to which is connected a crank arm 22, having its free end provided with a right angularly disposed cylindrical extension 23, formed with a reduced terminal 24'.

The pressure-actuated operating mechanism for the closing means comprises a cylinder 24 which is open at its upper end and connected with the fuel supply line 15 by integral superposed coupling extensions 26. The cylinder 24 is open at its top, as indicated at 27, and closed at its bottom as indicated at 28. Eccentrically of the bottom 28 is formed an opening 29 having a threaded wall for a purpose to be hereinafter referred to. Mounted on the upper end of the cylinder 24 is a stop member 30 in the form of a leather washer and which has its inner diameter materially less than the inner diameter of the cylinder 24 whereby the washer will project partly across the open upper end of said cylinder. Mounted on the stop member 30 is a metallic annulus 31 of the same outer and inner diameter with respect to the member 30. The member 30 and annulus 31 are secured to the upper end of the cylinder by the holdfast devices 32. The annulus 31 has its inner and outer edges registering with the edges of the member 30.

Operating within the cylinder 24 is a cup-shaped piston 33 which has its upper movement arrested by the member 30. Pivotally connected, at its lower end, as at 34, within the piston 33 intermediate the ends of the latter, is a piston rod 35, having its upper end formed with an opening 36, see Figure 5, through which extends the reduced terminal portion 24' of the extension 23. The reduced terminal portion 24' projects a substantial distance from the upper end of the piston rod 35 and carries retaining means, as indicated at 37 for connecting the extension 23 to the rod 35. The rod 35 is of a length to project above the cylinder 24 and through the annulus 31 when the piston 33 is seated on the bottom 28 of the cylinder 24. The piston 33 has its bottom 38 of convex-concavo cross section whereby when it is in engagement with the bottom 28 of the cylinder 24 it will project upwardly therefrom, note Figure 2. The piston 33 carries packing rings 39.

As each of the pressure controlling elements for the closure means operating mechanism is of the same construction, but one will be described, as the description of one will apply to the other. Each of said elements is coupled with a top wall 2 of the combustion chamber 1 and the top wall 40 of the storage space 12. Each of said elements, utilized separately of the mechanism for the automatic closure, is also used as an indicating or signalling element and comprises a base member in the form of an annular casting consisting of an upper portion 41, an intermediate portion 42 and a lower portion 43. The upper portion 41 is of slightly less outer

diameter than the intermediate portion 42 and the lower portion 43 is of slightly greater outer diameter than the intermediate portion 42 to provide a shoulder 44. The intermediate portion 42 is peripherally threaded as at 45. The upper portion 41 is formed with a pair of spaced openings 46, 47 and each of which has the walls thereof threaded. The intermediate portion 42 is provided with a vertically disposed opening 48 registering with the opening 46 and of less diameter than the diameter of the latter. The opening 48 is of uniform diameter throughout. The intermediate portion 42 is furthermore provided with an opening 49 which registers with the opening 47 but is of less diameter than the diameter of the latter. The opening 49 gradually decreases in diameter from its upper to its lower end whereby the wall thereof will be tapered. The bottom portion 43 is of greater height than the top or intermediate portions 41, 42, respectively, and is hollow to provide an annular chamber having therein a web 50 which depends from the intermediate portion 42 and is of less height than the height of the lower portion 43. The web 50 is cylindrical in contour and disposed centrally of the chamber 51 formed by the lower portion 43. The inner face of the lower portion 43 is integrally threaded as at 52 and engaging therewith is a closure 53, formed with a socket 54 for the reception of the lower end of the web 50. The lower part of the intermediate portion 42 is cut away to form a continuation of the chamber 51 as indicated at 55. Mounted in the opening 49 is a tapered fusible plug 56 which normally closes the chamber 51 to the opening 47. The top wall 2 of the combustion chamber 1 is formed with an opening 57 having a threaded wall which is engaged by the threaded intermediate portion 42 for the purpose of coupling the base member to said wall 2. When the base member of the pressure element is coupled or connected to the wall 2, the shoulder 44 abuts against the lower face thereof. The base member when coupled or connected to the wall 2 extends above and depends below the same. The height of the intermediate portion 42 is the same as the thickness of the top wall 2 of the combustion chamber 1. The plug 56 is disposed in horizontal alignment with respect to said top wall 2. Threadedly engaging with the wall of the opening 47 is a steam intake tube 58 having its upper end open, as at 59 and its lower end normally closed to the chamber 51, by the fusible plug 56. The intake tube 58 extends to a point adjacent the wall 40 and into a protecting cap 60 which extends above and is spaced throughout from the upper portion of the tube 58 and the space between the cap 60 and tube 58, which is indicated at 61 is formed with a passage whereby steam can

enter the tube 58 from the upper end thereof.

Threadedly engaging at its lower end with the opening 46 and of a length to extend through the wall 40 is a tube 62 for conducting steam for a purpose to be presently referred to. The wall 40 is formed with an opening having the wall thereof stepped and such opening is indicated at 63. The tube 62 extends through the opening 63 and through a plug 64, which has threaded engagement with the wall of the opening 63 and bears against a packing 65 to provide a steam tight joint between the tube 62 and wall 40. The tube 62 is permanently in communication with the opening 48 and chamber 51. As illustrated two pressure controlling elements are employed in the device, but it is to be understood that this number can be increased or diminished. The top wall 2 of the combustion chamber 1 will be provided with as many openings 57 as correspond to the number of pressure controlling elements employed and this statement also applies to the top 40 of the storage space 12. The protecting cap 60 is spaced and supported by any suitable means carried thereby so as to maintain it at the desired distance with respect to the upper terminal portion of the tube 58.

The simple indicating or signalling element is preferably positioned between the two pressure controlling elements and it consists of a tubular member formed of an upper portion 66, an intermediate portion 67 and a lower portion 68. The portion 66 is of less diameter than the portion 67 and the latter is of less diameter than the portion 68. The intermediate portion 67 is peripherally threaded and engages with the threaded wall of an opening 68 formed in the top wall 2 of the combustion chamber 1. The intermediate portion 67 is of a height corresponding to the thickness of the wall 2. The portion 66 projects above the wall 2 and the portion 68 depends therefrom. The inner face of the portion 66 is threaded as at 69 and engaging therewith is the lower end of an upstanding steam conducting pipe 70 of a length to terminate adjacent to the wall 40. Surrounding the upper portion of the tube or pipe 70, as well as being spaced therefrom is a protecting cap 71 and the space between the latter and the tube 70, which is indicated at 72 permits of a supply of steam to enter the opened upper end 73 of the tube 70. The inner face of the intermediate portion 67 gradually decreases in diameter from its upper to its lower end to provide a tapering wall 74 and seated against said wall throughout is a fusible plug 75. The plug 75 is arranged in horizontal alignment with respect to the top wall 2. The inner face of the lower portion 68 gradually increases in diameter from its upper to its lower end as indicated at 76. The tube 70 is provided for conducting steam from the storage space 12 130

into the combustion chamber of the engine to indicate a signal for a purpose to be herein-after referred to. The tube 70 is normally closed to the combustion chamber 1 by the 5 fusible plug 75. The protecting cap 71 is spaced and supported by any suitable means carried thereby so as to maintain it at the desired distance with respect to the upper terminal portion of the tube 70.

10 The pressure conducting line is indicated at 77 and has one of the steam conducting tubes 62, coupled therewith by a T-coupling 78 and such tube opens into the line 77 for the purpose of supplying steam thereto. The other 15 conducting tube 62 is connected to the upper end of the line 77 by an elbow coupling 79 and said other tube 62 communicates with the line 77 for the purpose of supplying steam thereto. The pressure conducting line opens into the 20 piston chamber 80 formed by the cylinder 24 and with reference to Figure 2 the line 77 has its lower end threadedly engaging with the wall of the opening 29 formed in the bottom 28 of the cylinder 24. Steam pressure is supplied into the space formed between the bottom 38 of the piston 33 and the bottom 28 of the cylinder 24.

With reference to Figure 2, the fuel supply line 15 includes a section 81 having a part 25 thereof providing the valve casing or housing 20. Each end of the section 81 is enlarged as at 82, 83 and interiorly threaded for coupling therewith adjacent pipe sections of the line 15. The inner end of the casing 20 is closed by a plate 85 and through which extends the reduced shank 84 extending from the inner end of the valve 18'. Carried by the shank 84 is a retaining means 86 for arresting the outward shift of the valve 18'. The valve 18' projects from the outer end of the casing 20 and is normally positioned in spaced relation with respect to the inner face of the plate 18. The casing or housing 20 is arranged in proximity to the upper end of the section 81 and the cylinder 24, which is formed integral with the coupling extensions 26, and is positioned a substantial distance below the casing 20. The coupling extensions 26 are integral with the section 81.

30 The fusible plugs 56 and 75 are protected from incrustation by the arrangement of the tubes 58 and 70 with respect to the protecting caps 60, 71. The wall of the opening 48, as well as the wall of the chamber 51 is also protected from incrustation. The fusible plugs are mounted in the top wall 2 of the combustion chamber. In other words the fusible plugs are in direct contact with the calefaction parts and by this arrangement 35 the temperature of the fuse plugs will be maintained always uniform to that of the calefaction parts. When the fuse plugs are melted or fused and their closure function impaired, owing to the manner of setting up 40 the pressure controlling and indicating ele-

ments it permits of new plugs to be conveniently positioned when occasion requires.

In connection with the manner in which the safety device operates it will be stated that when the boiler or steam generator is 45 working normally, the calefaction parts, among them the wall 2, are covered by water, whereby the calefaction parts will be maintained at a temperature equal to that of the water which is in contact with them; but 50 when said calefaction parts, that is the top wall 2 of the combustion chamber is clear of water, then the temperature thereof is increased. The plugs 56 and 75 are soldered in 55 position. When the temperature of the top wall 2 is increased, it is transmitted to the fusible plugs. When the temperatures of the top wall 2 and fusible plugs reach 350° C., the plugs melt whereby communication is established between the tubes 58 and 62 and between the tube 70 and the combustion chamber 1, and under such conditions a steam 60 current is supplied to the pressure conducting line 77 and a steam current is supplied to the combustion chamber 1. The steam current 65 travelling through the line 77 will be passed to the chamber 80, elevating the piston 33 and actuating the closing means for the pipe line 15 or an air intake closing means. The piston 33 when in its lowered position acts to 70 maintain the valve 18' open and when the piston 33 is acted upon by steam pressure it is elevated and whereby the valve 18' is closed. The cutting off of the fuel supply will provide for the extinguishing of the fire in the 75 combustion chamber avoiding thereby the serious risk that the boilers or steam generators will burst, and also prevent the deformation of the walls of the combustion chamber. The steam currents that come out 80 so much as to go into the combustion chamber as well as to the atmosphere, will indicate, respectively, that there is an improper 85 temperature in the calefaction parts.

It is thought the many advantages of a safety device, in accordance with this invention and for the purpose set forth, can be readily understood, and although the preferred embodiment of the invention is as illustrated and described, yet it is to be understood that 90 changes in the details of construction can be had which will fall within the scope of the invention as claimed.

What I claim is:

1. In an automatic safety device for a steam 95 generator of that type having a combined water and steam space over the crown sheet of the combustion chamber, the combination of a chambered base member adapted to be seated in and connected directly to the crown sheet, a steam conducting tube permanently 100 opening into the chamber of the base member and leading therefrom through said space for supplying steam to a steam pressure actuated 105 shut off mechanism, a steam intake tube 110

wholly within said space and having its respective ends opening into said space and the chamber of said base member, and a fusible plug within the base member, normally closing said intake tube to the chamber in said base member and fusing when the crown sheet reaches a temperature to melt the plug whereby communication is established between the intake tube and the chamber of said base member, said plug having its upper surface in horizontal alignment with the upper surface of said crown sheet.

2. In an automatic safety device for a steam generator of that type having a combined water and steam space over the crown sheet of the combustion chamber, the combination of a base member adapted to be seated in and connected to the crown sheet and having the lower portion thereof formed with a chamber, said base member further being formed with a pair of spaced steam passages extending through the upper portion thereof to the chamber in said base member, a steam conducting tube extending into one of said passages, communicating permanently with the chamber in the base member and leading therefrom through said space for supplying steam to a steam pressure actuated shut off mechanism, a steam intake tube wholly within said space and having its respective ends in communication with the other of said passages and said space, and a fusible plug in and normally closing said last mentioned passage to the chamber in the base member and fusing when the crown sheet reaches a temperature to melt the plug whereby communication is established between the intake tube and the chamber of said base member, said plug having its upper surface in horizontal alignment with the upper surface of said crown sheet and of less length than the passage in which it is associated.

3. In an automatic safety device for steam generators of that type having a combined water and steam space over the crown sheet of the combustion chamber, the combination of a base member adapted to be connected to said crown sheet and of a length to project above and depend below said sheet, said member formed with a chamber and an upper and an intermediate pair of openings, the intermediate openings communicating at their lower ends with said chamber through the top of the latter and at their upper ends with said upper openings, a steam intake pipe leading from said space to one of the upper openings, a steam discharge pipe leading from the other of said upper openings, a fusible plug mounted in one of said intermediate openings for normally closing the intake pipe to said chamber and the base member and fusing when the crown sheet reaches a temperature to melt the plug whereby communication is established between the intake tube and the chamber of said base member to pro-

vide for the passage of steam to said discharge pipe, said plug having its upper end flush with the upper face of the crown sheet, and a protecting cap adapted to be secured in said space and enclosing and spaced from the inlet end of said intake tube.

4. In a safety device for a steam generator of that type having a combined water and steam space over the crown sheet of the combustion chamber, in combination with a steam intake tube for communication at one end thereof with said space, means for controlling the passage of steam from said space through said tube, said means including a base member adapted to be connected to said crown sheet and of a length to project above and depend below said sheet, said base member provided with a steam outlet, an opening intermediate its ends and communicating with said outlet and an upper opening registering with the intermediate opening, said tube having its other end secured in said upper opening, a fusible plug mounted in said intermediate opening and normally closing it to said outlet and fusing when the crown sheet reaches a temperature to melt the plug whereby communication is established between the intake tube and said outlet to provide for the discharge of steam from said space, and a protecting cap adapted to be secured in said space and enclosing and spaced from the intake end of said tube.

In testimony whereof, I affix my signature hereto.

SALVADOR HERREJÓN LÓPEZ.
